DESIGN FOR A TOOTH BRUSH

Jonah Salit, New York, N. Y.

Application November 4, 1939, Serial No. 88,037

Term of patent 14 years

To all whom it may concern:

Be it known that I, Jonah Salit, a citizen of the United States and a resident of New York, in the county of Bronx and State of New York, have invented a new, original, and ornamental Design for a Tooth Brush, of which the following is a specification, reference being had to the accompanying drawing, forming part thereof.

The dominant feature of the design resides in the portion extending forwardly, to the left of line 5—5 of Figure 1.

I claim:

The ornamental design for a tooth brush, substantially as shown and described.

JONAH SALIT.
